CLAIM

An ornamental design for an office chair, as shown and
described in the attached drawings.

DESCRIPTION

FIG. 1 is a front view of a first embodiment of an office chair
embodying our design;

FIG. 2 is a top view thereof;

FIG. 3 is a left side view thereof, the right side view being
substantially a mirror image thereof;

FIG. 4 is a rear view thereof;

FIG. 5 is a left, rear isometric view thereof;

FIG. 6 is a front view of a second embodiment of an office
chair embodying our design;

FIG. 7 is a top view thereof;

FIG. 8 is a left side view thereof, the right side view being
substantially a mirror image thereof;

FIG. 9 is a rear view thereof; and,

FIG. 10 is a left, rear isometric view thereof.

The base for the office chair of the claimed design is
illustrated herein in phantom outline for environmental
purposes and forms no part of the claimed design.
